CLAIM

The ornamental design for a magnetic attachment mechanism for bone conduction hearing device, as shown and described.

DESCRIPTION

FIG. 1 is a top, front and left perspective view of a magnetic attachment mechanism for bone conduction hearing device, showing my new design;

FIG. 2 is a top view thereof;

FIG. 3 is a bottom view thereof;

FIG. 4 is a left view thereof, the right view is identical to the left view;

FIG. 5 is an enlarged front view thereof, the rear view is identical to the front view; and,

FIG. 6 is a left, bottom and front perspective view thereof.

1 Claim, 2 Drawing Sheets
